UNITED STATES PATENT OFFICE.

EDWIN V. WHITAKER, OF GLOVERSVILLE, NEW YORK.

WINDOW-SHADE.

SPECIFICATION forming part of Letters Patent No. 297,892, dated April 29, 1884.

Application filed February 28, 1884. (No model.)

To all whom it may concern:

Be it known that I, EDWIN V. WHITAKER, a citizen of the United States, and a resident of Gloversville, in the county of Fulton and State of New York, have invented certain new and useful Improvements in Window-Shades; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved window-shade. Fig. 2 is a perspective view of one of the supporting-brackets. Figs. 3 and 4 are detail views of the spring-bracket, and Fig. 5 is a similar view of the pivot-bracket.

Similar letters of reference indicate corresponding parts in all the figures.

My invention has relation to window-shades operated by springs; and it consists in the improved construction and combination of parts of the same, as hereinafter more fully described and claimed.

In the accompanying drawings, the letter A indicates a cornice, to the ends of which the spring-bracket B and the pivot-bracket C are secured, and which is clamped by two brackets, D, secured in the wall or window-frame, and forming two projecting lips, E, between which the cornice is held, thumb-screws F passing through the upper lips of the brackets, and bearing against the upper side of the cornice, preventing the cornice from slipping out from between the lips. The pivot-bracket C, in which the pivot G in the end of roller H turns, is provided with an inwardly-projecting base-plate, I, having two longitudinal slots, J, extending from its inner edge, and two fastening-screws, K, pass into the under side of the cornice, the slots sliding upon them, and their heads bearing against the under side of the base-plate, allowing the bracket to be adjusted upon these screws to accommodate rollers of different lengths. The spring-bracket is provided with a base-plate, L, secured by means of screws to the under side of the cornice, and the portion of the bracket projecting downward from the base-plate forms a

narrow cylindrical casing or barrel, M, the inner open side of which is covered by a recessed plate, N, secured removably to the same. The barrel has a central bearing, O, through which passes the outer portion of a shaft, P, to which the inner end of the helical spring Q is secured, the outer end of which spring is secured to the inner side of the barrel, in the same manner as the spring in a watch or clock. The outer end of the shaft is preferably square, adapted to be turned by a key or wrench, and a ratchet-wheel, R, is secured upon the shaft immediately above the spring, and engages a pawl, S, upon the under side of a cog-wheel, T, which turns and fits upon the shaft. This cog-wheel engages a pinion, U, secured upon the face of a cog-wheel, V, and this wheel meshes with a pinion, W, upon the end of a sleeve, X, which turns upon the reduced inner end, Y, of the shaft, and which sleeve is adapted to be inserted with its square or otherwise polygonous end Z into a correspondingly-shaped perforation in the end of the shade-roller. When the spring is wound slightly so as to give tension to it, and the shade is drawn down, the spring will be wound still tighter, so as to wind the shade upon the roller again, while it is unwinding itself.

For the purpose of preventing the spring, in unwinding itself, from winding up the shade, the rod B' at the lower end of the shade is loaded or otherwise weighted to overcome the tension of the spring; or other means may be provided to hold the shade down at different points of the window-frame, as in other spring-actuated roller-shades.

It will be seen that by having the operating-spring inclosed in one of the brackets, a shade and roller of any construction may be adapted to the brackets; and it will also be seen that the roller-bearing brackets being secured upon the cornice, and the cornice being held between the clamping-lips of the brackets, which may be secured into the wall or window-frame at any distance from each other, the roller may be used in a window in which a roller secured between brackets secured directly in the wall would have to be adjusted in length exactly to correspond to the width of the window, while this roller may be placed in any window, irrespective of its width, without any adjustment.

Having thus described my invention, I claim and desire to secure by Letters Patent of the United States—

1. The combination of a cornice having roller-bearing brackets, with brackets having projecting clamping-lips adapted to clamp the cornice, and having set-screws passing through the lips bearing against the cornice, as and for the purpose shown and set forth.
- 10 2. The combination, in a window-shade, of the roller, with a bracket having a longitudinally-slotted base-plate and screws passing through the slots, the said slots sliding upon the said screws, as and for the purpose shown and set forth.
- 15 3. The combination, in a window-shade, of the roller, with a bracket having the end of the roller pivoted in it, having slots in its base-plate extending from its inner edge, and sliding with the said slots upon screws, as and for the purpose shown and set forth.
- 20 4. In a widow-shade, the combination of a bracket forming a flat cylindrical casing or

barrel covered by a recessed plate, a helical spring secured to the inner side of the barrel 25 and to a shaft turning in the barrel, a shaft turning in the barrel, having the inner end reduced and provided with a ratchet-wheel, a cog-wheel turning upon the shaft and having a pawl engaging the ratchet-wheel, a cog- 30 wheel having a pinion meshing with the aforesaid cog-wheel, a sleeve having a pinion upon its inner end, turning upon the reduced inner end of the shaft, and having its inner end polygonous, and a shade-roller pivoted in 35 a bracket at its other end, and having a recess or perforation in its end adapted to receive the end of the sleeve, as and for the purpose shown and set forth.

In testimony that I claim the foregoing as 40 my own I have hereunto affixed my signature in presence of two witnesses.

EDWIN V. WHITAKER.
